PACKAGING TRAY OR THE LIKE

Morell J. Holden, Jr., Canarsie, N.Y., assignor to Mobil Oil Corporation, New York, N.Y.

Filed Mar. 19, 1973, Ser. No. 342,560

Term of patent 14 years

Int. Cl. D9—03

U.S. Cl. D9—243

FIG. 1

FIG. 2

FIG. 4

FIG. 3

FIG. 5

FIG. 6

FIG. 1 is a perspective view of a packaging tray or the like showing my new design;

FIG. 2 is a top plan view;

FIG. 3 is a side elevational view;

FIG. 4 is a cross-sectional view taken on line 4—4 of FIG. 2;

FIG. 5 is an end elevational view; and

FIG. 6 is a bottom plan view thereof.

I claim:

The ornamental design for a packaging tray or the like, substantially as shown.
